BOOK PROTECTOR

Robert Perry Sharp, Uvalde, Tex., assignor to
 Sharp & Company, Uvalde, Tex., a corporation
 of Texas

Application May 21, 1937, Serial No. 144,048

7 Claims. (Cl. 281—34)

This invention relates to book cover protectors or enclosures, and more particularly to a protector or enclosure formed from a sheet or sheets of suitable pliable and foldable material, such as cardboard.

Among the objects of the invention is the provision of a protector which requires no pasting nor similar securing together of parts, yet the protector will remain securely in place upon the book covers.

Another object is to provide a book cover protector, wherein pockets are provided for portions of flaps forming parts of the protector, these pockets retaining the flap portions in position and preventing accidental loosening of the protector.

Many book cover protectors are so complicated that it is difficult to adjust them to books. An object of this invention is to provide a simple arrangement of parts which entail but a few manipulations in order to fit the protector about books.

Other objects and advantages of this invention will be apparent during the course of the following detailed description, taken in connection with the accompanying drawing, forming a part of this specification and in which drawing:—

Figure 1 is a perspective view of the flattened blank from which the protector is made, with a book, to which the blank is to be fitted, in place and showing the first step of fitting the blank to the book.

Figure 2 shows, in perspective, the next step in the formation of the protector.

Figure 3 is a perspective view showing the protector partly about the book, one end flap being folded over the cover of the book.

Figure 4 shows, in perspective, the method of pocketing certain portions of the top and bottom flaps.

Figure 5 is a perspective view showing the protector in one of its final positions about the book covers.

Figure 6 is a section substantially on the line 6—6 of Figure 5, showing the positions of the flaps and tabs at the outer corners of the book covers of Figure 5.

Figure 7 is a perspective view illustrating an alternate method of pocketing certain portions of the top and bottom flaps, differing somewhat in the arrangement of parts over Figure 4.

Figure 8 is a section substantially upon the line 8—8 of Figure 7, showing the positions of the flaps and tabs at the outer corner of the book covers of Figure 7.

55 In the drawing, wherein for the purpose of illus-

tration is shown a preferred embodiment of the invention and wherein similar reference characters designate corresponding parts throughout the several views, the letter A may designate generally a book and the letter B the novel protector or enclosure therefor.

Shown, by way of example, is the book A which includes a conventional front cover 10 having an outer face 11 and an inner face 12, a rear cover 13 having an outer face 14 and an inner face 15, 10 and a back 16. While the term "book" is employed, it should be understood that the novel protector may be employed in protecting magazine covers, portfolio covers, snap shot album covers and the like.

15 The novel protector enclosure B initially comprises one or more sheets of suitable material. In the example shown, one sheet 20 is employed and it is preferred to employ but one sheet in order to cover or protect a book. This sheet is 20 preferably of easily foldable material, such as paper, cardboard, canvas, leather or the like, and is preferably rectangular, having substantially paralleling side edges 21 and 22, and substantially paralleling end edges 23 and 24, joining the side 25 edges 21 and 22.

With the top, bottom and end edges 25 to 28 of the protector body determined in any suitable way, as by creasing or marking, as is clearly illustrated in Figure 1, four V-shaped cuts or cut 30 outs 29 are made, with the apex of one cut at each of the corners of the protector body and the mouths of the cuts 29 in the side edges 21 and 22 of the sheet 20.

35 Suitable paralleling transverse slits 30 may now be made, as in conventional practice, from the side edges 21 and 22 towards each other and spaced apart from the transverse medial line of the protector, these slits extending to the top and bottom edges 25 and 26 of the protector, as in 40 ordinary practice, for accommodating the protector to the back 16 of the book. However, it is preferred that these transverse slits 30 be spaced apart a distance substantially greater than the width of the back 16, as illustrated in and for 45 the same reasons as set out in my co-pending application Serial Number 142,255, filed May 12, 1937.

The next slits as provided, are very important ones. These slits 31 may be termed longitudinal 50 slits, and one extends from the apex of each cut 29 along the top or bottom edge 25 or 26, as the case may be, towards the opposite slit 31 or, in other words, towards the back-covering portion of the protector, as shown in Figure 2. It will be 55

noted that each of these slits 31 is at least as long as the distance from an end edge 23 or 24 of the sheet 20 to an end edge 27 or 28 of the protector. Such a length of slit 31 is absolutely necessary and, while it may not be less, the length may be slightly more.

With the cuts 29 and slits 30 and 31 made, there are provided two flaps 32, each defined by a cut 29, sheet edge 21, slit 30, protector edge 25 10 and slit 31, two similar bottom flaps 33, each defined by a cut 29, sheet edge 22, slit 30, protector edge 26 and slit 31, two similar back flaps, one being the top flap 34 defined by two slits 30, sheet edge 21 and protector edge 25, and the 15 other, being the bottom flap 35, defined by two slits 30, sheet edge 22 and protector edge 26, and two end flaps, one 36 defined by two cuts 29, sheet edges 21, 22 and 23 and protector edge 27, and the other 37 defined by two cuts 29, 20 sheet edges 21, 22 and 24 and protector edge 28. The end portions of the end flaps 36 and 37 may be termed tabs 38 to 41. Specifically, tab 38 is defined by a cut 29, portions of the sheet edges 21 and 23 and the prolongation 42 of the 25 protector edge 25, tab 39 is defined by a cut 29, portions of the sheet edges 22 and 23 and the prolongation 43 of the protector edge 26, tab 40 by a cut 29, portions of the sheet edges 21 and 24 and the prolongation 44 of the protector edge 25, and tab 41 by a cut 29, portions of the sheet edges 22 and 24 and prolongation 45 of the 30 protector edge 26. Each flap is adapted to be folded upon its respective edge 25 or 26, and each tab upon its respective prolongation 42 to 45 of the 35 edges 25 and 26.

Referring again to the flaps 32 and 33, with their slits 31, these slits provide, in effect, tabs 46 and 48 for the flaps 32 and tabs 47 and 49 for the flaps 33, these tabs 46 to 49 extending from 40 the corners of the protector, towards the transverse medial line of the protector.

With the novel protector as described, the back flaps 34 and 35, may be folded as shown in Figure 2 and the protector is ready to receive the 45 book A, laid upon it substantially as the book A is shown laid upon the sheet 20 in Figure 1. First, the end flaps 36 are folded against the inner faces 12 and 15 of the book covers 10 and 13 and then their tabs 38 to 41 may be tucked 50 in to lie between the outer faces 11 and 14 of the book covers 10 and 13 and the body portion 55 of the protector, as may be seen in Figures 3, 4 and 6. This provides a pocket at each corner of the folded protector so that when the top and bottom flaps 32 and 33 are folded against the inner faces 12 and 15 of the book covers 10 and 13 respectively, the tabs 46 to 49 may be tucked or inserted into these pockets, as in Figure 4. This effectively secures the protector to 60 the book without the use of adhesive or the like. Yet, by withdrawing the tabs 46 to 49 from the pockets, the protector may be easily removed from the book and, if required, flattened out.

Instead of tucking the tabs 38 to 41 as described, they may be folded to lie between the end flaps 36 and 37 and the inner faces 12 and 15 of the covers 10 and 13, and the tabs 46 to 49 may be inserted into the pockets provided by the tabs 38 to 41 and the end flaps 36 and 37, 70 as in Figures 7 and 8. This also effectively secures the protector to the book without the use of adhesive and the like yet, when desired, the tabs 46 to 49 may be withdrawn and the protector folded out flat.

In either case, pockets are provided at the four corners of the protector to receive the tabs 46 to 49. It has been discovered that slits at or adjacent the corners of the protector, to receive portions of tabs, tear very readily or cause the tabs to tear, even when tough material is used for the protector, but the pockets herein provided do not tear nor do the tabs inserted therein tear.

Since no adhesive is used, there is a free play 10 of parts, due in part to the fact that the tabs 46 to 49 are loosely inserted into the pockets and, therefore, there is no gripping relation between the walls of the pockets and the tabs, but there is a free play of parts, which is often important 15 since, in opening and closing a book protected by a covering, there must be some allowance for play.

The extra thickness of material at the corners, as shown in Figures 6 or 8, protect the corners 20 of the book materially.

Various changes may be made to the form of invention herein shown and described, without departing from the spirit of the invention or the scope of the claims.

What is claimed is:

1. In a book cover protector, a body portion having flaps extending from its top, bottom and ends, the end flaps terminating at one end in top tabs and at the opposite end in bottom tabs, said 30 tabs extending in the same direction as the top and bottom flaps, said protector having cut outs extending between said top flaps and said top tabs and between said bottom flaps and said bottom tabs, said tabs being adapted to be turned 35 towards each other and disposed in contact with the covers protected by said protector, whereby said tabs and portions of said end flaps provide pockets at the corners of said protector, each of said top and bottom flaps having a longitudinally 40 extending slit extending, from the junctures of each top and bottom flap with said end flaps, towards each other, the slotted portions of said top and bottom flaps being adapted to extend into said pockets.

2. In a book cover protector, a body portion having flaps extending from its top, bottom and ends, the end flaps terminating at one end in top tabs and at the opposite end in bottom tabs, said 50 tabs extending in the same direction as the top and bottom flaps, said protector having cut outs extending between said top flaps and said top tabs and between said bottom flaps and said bottom tabs, said tabs being adapted to be turned towards each other and disposed in contact with the covers protected by said protector, whereby said tabs and portions of said end flaps provide pockets at the corners of said protector, each of said top and bottom flaps having a longitudinally 55 extending slit extending, from the junctures of each top and bottom flap with said end flaps, towards each other, the length of said slit being substantially as great as the width of each end flap and said slits extending along the longitudinal edges of said protector.

3. In a book cover protector, a body portion having top flaps, bottom flaps and end flaps, said end flaps terminating in tabs extending longitudinally of said end flaps, a pair of said top flaps and a pair of said bottom flaps having tabs extending longitudinally of said pairs of flaps from the outer ends thereof, tabs on said end flaps adjacent tabs on said top and bottom flaps being separated by substantially V-shaped cut outs, said first named tabs being adapted to be folded 70 75

upon said end flaps and said end flaps and first named tabs being adapted to be folded over to substantially parallel said body portion, said top and bottom flaps being adapted to be folded over 5 to substantially parallel said body portion, with each of said last named tabs lying between an end flap and one of said first named tabs.

4. In combination with a book, including covers, a book cover protector including a body portion having top flaps, bottom flaps and end flaps, said end flaps terminating in tabs extending longitudinally of said end flaps, a pair of said top flaps and a pair of said bottom flaps having tabs extending longitudinally of said pairs of flaps 10 from the outer ends thereof, said first named tabs being folded upon said end flaps and said end flaps and first named tabs being folded over the faces of book covers at the free ends of said covers, said top and bottom flaps being folded over other portions of the faces of said book 15 covers at the tops and bottoms of said covers, with each of said last named tabs lying between an end flap and one of said first named tabs and in contact with at least one of them.

20 5. In combination with a book having covers, a book cover protector including a body portion having top flaps, bottom flaps and end flaps, said end flaps terminating in tabs extending longitudinally of said end flaps, a pair of said top flaps 25 and a pair of said bottom flaps having tabs extending longitudinally of said pairs of flaps from the outer ends thereof, said first named tabs being folded upon said end flaps and said end flaps and first named tabs being folded over the 30 faces of said book covers at the free ends of said covers, said top and bottom flaps being folded over other portions of the faces of said book covers at the tops and bottoms of said covers, with each of said last named tabs lying between 35 an end flap and one of said first named tabs and in contact with one of said end flaps.

6. In combination with a book having covers, a book cover protector including a body portion having top flaps, bottom flaps and end flaps, said end flaps terminating in tabs extending longitudinally of said end flaps, a pair of said top flaps and a pair of said bottom flaps having tabs extending longitudinally of said pairs of flaps from the outer ends thereof, said tabs of said top and bottom flaps being separated from said body portion by slits, said first named tabs being folded upon said end flaps and said end flaps and first named tabs being folded over the faces of said book covers at the free ends of said covers, said top and bottom flaps being folded over other portions of the faces of said book covers at the tops 10 and bottoms of said covers, with each of said last named tabs lying between an end flap and one of said first named tabs, and in free sliding contact with them. 15

7. In a book cover protector, a body portion 20 having flaps extending from its top, bottom and ends, the end flaps terminating at one end in top tabs and at the opposite end in bottom tabs, said protector having V-shaped cut outs disposed between said top flaps and top tabs and between 25 said bottom flaps and bottom tabs, said protector being provided with slits extending from the apices of said V-shaped cut outs towards each other along the junctures of said top and bottom flaps and said body portion, whereby a portion 30 of each of said top and bottom flaps constitutes a slotted portion, said tabs being adapted to be turned towards each other and disposed in contact with the covers protected by said protector, whereby said tabs and portions of said end flaps provide 35 pockets at the corners of said protector, said slotted portion being adapted to extend into said pockets.
